TOE LASTING MACHINES

Andrew J. Gilbride, Swampscott, Mass., assignor to United Shoe Machinery Corporation, Flemington, N.J., a corporation of New Jersey

Filed May 19, 1961, Ser. No. 111,241

20 Claims. (Cl. 12—8.8)

This invention relates to machines for lasting the toe ends of shoes and more particularly to toe lasting machines of the type wherein the upper materials are shaped around the toe end of a last as a result of relative heightwise movement between the shoe on a support and upper shaping means and are stretched about the last by a pull exerted thereon by a member arranged to engage the upper materials during such relative heightwise movement. Following the shaping and stretching of the upper materials around the toe end of the last, the lasting margin of the upper materials is wiped inwardly over and pressed against the bottom of the insole at the toe end of the shoe by toe wipers thus to complete the toe lasting operation by securing the lasting margin of the upper materials to the insole in lasted position usually by means of a suitable adhesive.

Although machines of the above-mentioned type have proved to be generally satisfactory in operation and are quite widely used in the trade, as previously constructed they impose certain limitations and inconvenience from the standpoint of wholly efficient and versatile operation. Thus, where the lasting margin is to be secured in lasted position by means of adhesive, it is usually necessary to apply this adhesive to the upper and/or insole before the shoe is presented to the machine, and thereafter the shoe thus treated must be lasted at a rather definite time when the previously applied adhesive has dried to the desired tacky condition. Also, the use of improved adhesives of the thermoplastic and/or thermosetting type is obviously prohibited. In addition, in the machines of this type as heretofore proposed no opportunity is afforded during the lasting operation for the operator to perform any hand operations on the shoe such, for example, as the trimming out of the box toe and lining at the toe end of the shoe or hand pincering of the upper, following the upper shaping operation but prior to the wiping of the lasting margin inwardly over the toe end of the insole. It is, therefore, a principal object of this invention to provide a novel and improved toe lasting machine of the aforementioned type wherein these various limitations are removed and attendant inconveniences avoided.

With the foregoing object in view, the herein illustrated machine, which has a support for a shoe on its last and upper shaping means arranged for relative heightwise movement to effect the shaping of the upper materials around the toe end of the last, together with means for effecting such relative heightwise movement, and a member for engaging the upper materials to cause a pull to be exerted on the upper materials tending to stretch them about the last, is provided with means for supporting the aforementioned cooperating member mounted for movement from an inoperative position to an operative position, together with means for moving and holding this supporting means in operative position during the relative heightwise movement between the shoe support and the upper shaping means, and means for moving the supporting means to its inoperative position at the conclusion of such relative heightwise movement, thereby to retract the aforementioned member from the upper materials and the toe end of the shoe. Thus, prior to the operation of separately controlled toe wipers, the operator is afforded access to the toe end of the shoe and also to the lasting margin of the upper materials for the purpose of performing

2

ing any of the above-mentioned hand operations including, of course, the application of a suitable adhesive to the upper and/or insole. Preferably, and as herein illustrated, the control means for the wiper operating means is also adapted to effect a return of the supporting means to operative position so that the mentioned cooperating member may be effective for controlling the lasting margin of the upper materials as it is wiped inwardly over the insole by the wipers.

More particularly, in the herein illustrated machine, fluid pressure operated means are provided for effecting the relative heightwise movement between the shoe support and a toe band, which serves as the upper shaping means, and also for advancing and closing the wipers, together with separate manually operable control means for each of these fluid pressure operated means, while a retarder for cooperating with the toe band and a holdown for engaging the insole are associated with the above-mentioned supporting means which is movable to and held in operative position by fluid pressure operated means and is moved to its inoperative position by spring means. The last-mentioned fluid pressure means is connected to exhaust at the conclusion of the relative heightwise movement between the support and the toe band to cause the spring means to move the supporting means to its inoperative position and the manually operable means for controlling the fluid pressure operated means for advancing and closing the wipers is also adapted to render the fluid pressure operated means associated with the supporting means operable to return the supporting means to operative position so that the retarder is effective to control the lasting margin of the upper materials as the lasting margin is wiped inwardly over the toe end of the insole by the wipers.

Another object of the invention is to improve the action of the wipers in pressing the lasting margin of the upper materials against the insole of the shoe being lasted as the wipers are advanced and closed to wipe the lasting margin inwardly over the insole. With this object in view, in the herein illustrated machine fluid pressure operated means are provided for effecting relative movement between the wiper head and a shoe support in a direction to cause the wipers to press the upper materials against the insole, together with means operable in response to the advancing and closing movements of the wipers for controlling the pressure of operating fluid supplied to the fluid pressure operated means, thereby to vary the force exerted on the lasting margin of the upper materials by the wipers as the wipers are advanced and closed. More particularly, a pressure regulating valve having a displaceable member for controlling the pressure of the operating fluid is provided, together with a cam movable in response to the advancing and closing movements of the wipers for displacing the aforementioned displaceable member thus to vary the force exerted by the wipers on the lasting margin as the wipers are advanced and closed.

The above and other objects and features of the invention will appear in the following detailed description of the preferred embodiment thereof illustrated in the accompanying drawings, and will be pointed out in the claims.

In the drawings,

FIG. 1 is a view in perspective of a toe lasting machine embodying the features of this invention;

FIG. 2 is a plan view of the machine shown in FIG. 1;

FIG. 3 is a view in side elevation of the upper portion of the machine;

FIG. 4 is a view in side elevation, at an enlarged scale and with certain features in vertical section, of a portion of the machine which is shown in FIG. 3;

FIG. 5 is a view in horizontal section substantially on line V—V of FIG. 4 and looking in the direction of the arrows;

FIG. 6 is a view in elevation of the upper part of that portion of the machine shown in FIG. 4 as viewed from the left-hand side thereof;

FIG. 7 is a view in elevation of another part of that portion of the machine shown in FIG. 4 as viewed from the right-hand side thereof;

FIG. 8 is a plan view at an enlarged scale looking from below of that part of the machine shown in FIG. 7;

FIGS. 9, 10 and 11 are, respectively, views in side elevation, front elevation, and plan of a shoe rest forming a part of the machine;

FIG. 12 is a view in side elevation of a portion of the machine showing especially the toe rest and a toe pad, together with associated operating elements;

FIG. 13 is a view in end elevation of the parts shown in FIG. 12 as viewed from the left-hand side of that figure;

FIGS. 14, 15 and 16 are step views showing the operating elements in different positions assumed during the operation of the machine;

FIG. 17 is a detailed view, partly in vertical section, of a portion of the machine, and

FIG. 18 is a schematic drawing of the fluid pressure operating system and also showing various operating elements more or less diagrammatically.

Referring to these drawings, the operating elements of the machine, which are shown as a whole in FIG. 1, include a pair of wipers 20, 20, FIG. 2, a toe band 22, a retarder 24, and an insole holdown 26, FIGS. 4, 12, 14-16. During the operation of the machine, the shoe S being lasted, herein illustrated as comprising upper materials, indicated generally by the reference character U, assembled on a last L, together with an insole I, is clamped against a shoe rest 30 by a toe pad 32, and is held against heelward movement by means of a heel band 34, FIGS. 2 and 3. These operating elements and shoe supporting parts are mounted on a fabricated frame construction, indicated generally by the reference character 40, and herein referred to as the frame, with which the several operating cylinders and pistons, control valves, pressure gages, and other components of the fluid pressure operating system are associated.

The wipers 20, 20 are mounted in a wiper head 50 which contains the usual wiper actuating cams, not shown, which are operated by means of a rod 52, FIG. 3. As in toe lasting machines of this general type, the wiper head is mounted for angular adjusting movements about a horizontal and longitudinally extending axis on a table 54 which, in turn, is pivotally mounted on the frame 40, by means of trunnions 56, 56, FIG. 2, for swinging movements about a horizontal and transversely extending axis. Also carried on the table 54 is a cylinder 58 in which there is a piston 60, FIG. 18, which is connected to the wiper operating rod 52. When fluid under pressure is admitted to this cylinder through a conduit 61, the piston 60 will be moved to the right, against the resistance of a return spring 63, thereby advancing and closing the wipers 20, 20. At its free end, the table 54 is connected to the rod 62 of an operating piston 64, FIG. 18, in the manner more particularly shown in FIG. 17. Referring to that figure, a pin 68, carried by the table 54, extends through a pair of slots formed in a sleeve member 70 which is threaded onto the piston rod 62, only one of these slots appearing in FIG. 17, and there identified by the reference character 72. This sleeve member is provided with an axial bore 74 in which there is slidably received a plunger 76, urged yieldingly against the pin 68 by means of a compression spring 78. As will be apparent, when the piston 64, which is operable within a cylinder 80 mounted on the frame 40, FIGS. 1 and 3, is actuated, as a result of the admission of fluid under pressure to cylinder 80 through a conduit 82, to swing the table 54 up-

wardly, counterclockwise as viewed in FIG. 3, the pin 68 will be engaged by the lower ends of the slots 72, thus to provide a positive action of the piston on the table. On the other hand, however, when the piston 64 is actuated, as a result of the admission of fluid under pressure to the opposite end of the cylinder through a conduit 84, to swing the table 54 downwardly, clockwise as viewed in FIG. 3, a yielding action will be obtained until the upper ends of the slots 72 engage the pin 68.

The toe band, which is indicated generally by the reference character 22, comprises a piece of non-metallic material 90 having a low coefficient of friction and of substantially triangular cross section secured to a U-shaped strip of resilient metal 92, FIG. 4. This toe band is supported and operated by mechanism which is substantially the same as that disclosed in a copending and allowed United States application, Serial No. 859,485, filed on December 14, 1959, now Patent No. 2,986,753, granted June 6, 1961, in the name of the present inventor, and to which reference may be made for specific details of construction not herein described. Accordingly, this toe band is supported at its outer ends by means of a pair of links 94, 94, FIGS. 2 and 18, which are connected to an equalizing lever 96 carried on an operating lever 98 which is pivotally mounted on the wiper head 50. The band is also supported, at its toe end, on a block 100 guided for movement on the wiper head 50 to the right as viewed in FIG. 4, and toward the toe end of the shoe being lasted to the extent determined by a suitable stop, not shown, but which may correspond to the stop arrangement provided in the machine of the mentioned application.

As is shown in FIG. 2, at their outer ends the links 94, 94 are provided with angularly disposed slots 110 which are adapted to cooperate with pins 112 to cause the band to close around the toe end of the shoe as it is moved to the right, FIG. 4, in response to a counterclockwise swinging movement of the lever 98, FIG. 18, which is imparted thereto by means of a piston 116 mounted in a cylinder 118, see also FIG. 2, when fluid under pressure is admitted to this cylinder through a conduit 119. Pivotally mounted on the aforementioned block 100 are a pair of bell-crank levers 120, 122, FIG. 4, having pressure pads for engaging the opposite sides of the toe band adjacent to its toe end, FIG. 18, and adapted to be actuated by an oppositely moving cylinder 124 and piston 126, when fluid under pressure is admitted to cylinder 124 through a conduit 125, in the same manner as in the arrangement shown in the mentioned application.

The retarder, which is indicated generally by the reference character 24, comprises two similar and arcuately shaped blades 150, 150 each secured with a capability of angular adjustment about their common meeting point "x" by means of clamp screws 152, 152 and slots 154, 154, FIG. 8, to the lower side of a block 156, FIGS. 4 and 7. This block is mounted on a supporting arm 160 by means of upper and lower parallel links 162, 164, see especially FIG. 4, the arm 160 being pivotally mounted by means of a cross shaft 166 on a bracket 168 which is fastened to the upper side of the wiper head 50. The arm 160 comprises two parallel vertically extending portions, FIG. 5, which are joined together at their upper ends by a transversely extending cross plate 170 on which there are mounted two cylinders 172, 174, FIG. 6, and see also FIG. 18. Connected to the arm 160 adjacent to the cross plate 170 is the piston rod 180 of a piston 182, FIG. 18, which is received within a cylinder 184, FIG. 3. When fluid under pressure is admitted to the cylinder 184, through a conduit 186, the arm 160 will be held in the position in which it is shown against the resistance of a tension spring 188.

Formed integrally with the link 162 is an arm 190 which extends upwardly in alignment with an adjustable stop screw 192 and the end of the rod 194 of a piston 196 in the cylinder 172, FIG. 3. A coil spring 198 holds

the arm 190 against the stop screw 192 with the block 156 and retarder 24 in the positions shown in FIG. 4 when the cylinder 172 is connected to exhaust through a conduit 200, see also FIG. 18.

The insole holdown, which is indicated generally by the reference character 26, comprises a strip of metal bent into an arcuate shape and secured to the lower end of an L-shaped lever 210. This lever is pivotally mounted on the lower end of a slide 212 by means of a pin 214, FIG. 4, and has an upper arm 216 which is held yieldingly against a stop pin 217 by a compression spring 218. The slide 212 is received within a guideway 230 formed in the block 156, FIG. 5, and has connected to its upper end one arm 232 of a bell-crank lever 234. The other arm 236 of this bell-crank lever is held yieldingly, by means of a spring 238, against the end of the rod 240 of a piston 242 which is received within the cylinder 174, FIG. 4, mentioned above, and which is connected also to the conduit 200. When fluid under pressure is admitted to the conduit 200 and thence to cylinders 172, 174, in a manner to be described below, the retarder 24 and the insole holdown 26 will be moved from the positions in which they are shown in FIG. 4, to the positions shown in FIG. 14.

The shoe rest 30, which is generally triangular in shape, see FIG. 11, and provided on its lower surface with serrated bosses 250, 250, is formed integrally with an arm 252 which is pinned to a shaft 254, FIGS. 2 and 10. This shaft has a portion of reduced diameter 256 which is journaled in, and projects through, a transverse bore 258 formed in one end of a second shaft 260, see also FIG. 9. The shaft 260 is journaled in a bearing bore 262 formed in a bracket 264 which is secured to the machine frame 40. Pinned to the end of the shaft 254 which projects through the bore 258 is an arm 266 through which there is threaded an adjusting screw 268 provided with a hand knob 270. Similarly, there is pinned to the other end of the shaft 260 an arm 272 through which there is threaded an adjusting screw 273 provided with a hand knob 274, FIG. 10. Coil springs 276 and 278, respectively, serve to hold the ends of the aforementioned adjusting screws against cooperating abutment surfaces, as shown in FIGS. 9 and 10. As will be apparent, by appropriate use of the adjusting screws 268 and 273, the position of the shoe rest 30 may be varied to accommodate different operating conditions.

The toe pad 32 is mounted on the upper end of a post 280 which is slidably received within a bore 282 formed in a guide block 284 mounted on the front portion of the machine frame 40, FIG. 12. Secured to the lower end of this post is a piston rod 286 which extends upwardly from a piston 288 which is received within a cylinder 290 mounted on a plate 291, formed integrally with the aforementioned block 284, by means of a sheet metal bracket 293. When fluid under pressure is admitted to this cylinder, through a conduit 292, see also FIG. 18, the toe pad will be elevated as shown in FIG. 12 to clamp the toe end of a shoe against the shoe rest 30.

The toe pad is locked in shoe clamping position, thus to provide an unyielding support for the shoe during the operation of the wipers 20, 20 to apply pressure on the overwiped lasting margin of the upper materials, in the following manner. Cut in the lower portion of the post 280 are a series of rack teeth 296, and meshing with these teeth is a toothed quadrant 298, FIG. 13. This quadrant is pinned to a short shaft 300 which is journaled in and projects rearwardly of the block 284. Secured to the rearward projecting portion of the shaft 300 is a second quadrant 302 having on its outer arcuate surface a series of ratchet teeth 304. Pivotal mounted, by means of a shaft 306, on a block 308 secured to the plate 291, is a pawl 310. A coil spring 312 connected to this pawl is adapted to withdraw the pawl from engagement with the teeth 304 when fluid under pressure is exhausted from the lower end of a cylinder 314, in which there is a piston

316 having a piston rod 318 in alignment with this pawl, through a conduit 320. On the other hand, as will be apparent, when fluid under pressure is admitted to this cylinder, the pawl 310 will be moved to the locking position in which it is shown in FIG. 13.

The heel band 34, which is of conventional construction, is supported at its opposite ends on arms 330, 330 which are adjustably connected to a pair of operating rods 332, 332 in the usual manner. These rods are slidably mounted in suitable guideways associated with the machine frame 40 and are connected together at their inner ends by means of a channel-shaped crosspiece 336, FIG. 3. Slidably received within aligned holes in flanges associated with this crosspiece is the end portion 338 of a piston rod 340 which is of reduced diameter to form a shoulder 342, and threaded on the extreme end of this piston rod are a pair of nuts 344. This piston rod extends forwardly from a piston 346, received within a cylinder 348, see also FIG. 18, which cylinder is mounted on a bracket 350 carried on the machine frame 40, FIG. 3. When fluid under pressure is admitted to one end of this cylinder through a conduit 352, the rods 332, 332 will be moved to the left, FIG. 3, and the heel band 34 will be brought into engagement with the heel end of a shoe 25 in the machine. On the other hand, when fluid under pressure is admitted to the opposite end of the cylinder 348 through a conduit 354 and at the same time exhausted from the other end of the cylinder through the conduit 352, the rods 332, 332 will be moved to the right 30 thereby withdrawing the heel band from the shoe.

To hold the heel band immovably in shoe engaging position during the operation of the wipers 20, 20, a pawl 360 is pivotally mounted on a block 362 carried by the crosspiece 336, this pawl having a bifurcated arm 364 which straddles the reduced end portion 338 of the piston rod 340. A leaf spring 366 is arranged to swing the pawl in a clockwise direction and into engagement with ratchet teeth 368 formed on a plate 370 mounted on the machine frame 40 when the piston 346 and rod 340 are moved to the left, FIG. 3. On the other hand, when this piston and the piston rod are moved in the opposite direction, the shoulder 342 on the piston rod will engage the bifurcated arm 364 and withdraw the pawl from engagement with the ratchet teeth 368, thereby freeing the rods 332, 332 for movement to the right to withdraw the heel band 45 from engagement with the shoe.

Referring to FIG. 18, the flow of fluid under pressure from a main supply line 400, which is connected to a source of fluid under pressure, e.g., compressed air, not shown, to the several cylinders mentioned above, as well as the exhaust from these cylinders, are controlled by four operator-actuated valves 402, 404, 406 and 408 which are of conventional construction and diagrammatically illustrated in this figure. The valve 402, which is arranged to be shifted back and forth between two positions in response to successive actuations of a knee pad 410, FIG. 1, connects the conduit 354, mentioned above, and a conduit 412, to the main supply line 400 when it is in the position shown in FIG. 18, and connects the mentioned conduits to exhaust and conduits 414, 416 and 418 to the main supply line 400 when in its other position. Referring again to FIG. 1, the knee pad 410 is operatively connected to a pawl 420 arranged to actuate a valve operating cam 422 in step-by-step rotary movements, which movements serve to shift the valve between its two positions. The conduit 292 which leads to the toe pad operating cylinder 290, is connected directly to the conduit 414, while the conduit 352, which leads to one end of the cylinder 348, is connected to the conduit 414 through a suitable flow-control valve 424 and one-way check valve 426. A similar flow control valve 428 and check valve 430 are associated with the conduit 354. The conduit 320, which leads to the pawl operating cylinder 314, FIG. 13, is connected to the conduit 414 through a sequence valve 432.

With the arrangement so far described, when the valve 402 is in the position shown in FIG. 18, the toe pad 32 will be lowered, as shown in FIG. 4, and the heel band 34 will be retracted away from the shoe S. Upon operation of the knee pad 410 to shift the valve 402 to its other position, the toe pad will be elevated by the piston 288 to clamp the toe end of the shoe against the shoe rest 36, as shown in FIGS. 12 and 14 to 16, and the heel band 34 will be moved into engagement with the heel end of the shoe by the piston 346, as shown in FIG. 18, and will be locked in this position by the pawl 360, FIG. 3. Now, as pressure builds up in the conduit 414, the sequence valve 432 will open and admit fluid under pressure to the conduit 320, thereby causing the piston 316 to actuate the pawl 310 and lock the toe pad in shoe clamping position. At this time, as will presently appear, fluid under pressure is admitted to the cylinder 184 and will have been exhausted from cylinders 172 and 174 so that the arm 160, block 156 and retarder 24, and slide 212 and the holdown 26, will be held in the positions in which they are shown in FIG. 4. Thus, the toe end of the shoe, as it is presented to the machine, may be brought into engagement with the retarder, see FIG. 4, and located in a lengthwise direction in the machine before it is clamped against the shoe rest, FIG. 12.

The valve 404, which is of conventional construction and diagrammatically illustrated in FIG. 18, is adapted to be moved, by the depression of a hand lever 434, FIG. 2, from the intermediate position shown in FIG. 18, to an operative position in which two conduits 436 and 438 are connected to the main supply line 400, and by the lifting of this hand lever to another position in which these conduits are connected to exhaust. The conduit 209, which leads to the two cylinders 172, 174, associated, respectively, with the retarder 24 and the insole holdown 26, is connected to the conduit 436 through a pressure regulator valve 440. Conduits 119 and 125 which lead, respectively, to the toe band operating cylinders 118 and 124, are connected to the conduit 436 through pressure regulator valves 442 and 444, while the conduit 82 which leads to the lower end of the cylinder 80, see FIG. 3, is connected to the conduit 436 through a so-called direction valve 446, a pressure regulator valve 448 and a sequence valve 450.

When the valve 404 is thus moved to its operative position, fluid under pressure is admitted to the cylinders 172, 174, 118 and 124 through the mentioned pressure regulator valves. Accordingly, toe band 22 will be moved by piston 114 and by cylinder 124 and piston 126 from a retracted position, see FIG. 4, to a projected and operative position, FIG. 14, determined by suitable stops, not shown, as in the toe band operating mechanism described in the above-mentioned application, while the retarder 24 and insole holdown 26 will be moved to their operative positions as is also shown in FIG. 14. Thus the retarder 24 will clamp the upper materials U yieldingly against the top of the toe band, while the holdown 26 will bear against the insole I in a location adjacent to the extreme toe end of the shoe, FIG. 14. As pressure now builds up in the conduit 436 to a value sufficient to open the sequence valve 450, fluid under pressure will then be admitted to the conduit 82 and, inasmuch as the direction valve 446 will be opened by pressure in the conduit 82, fluid under pressure will flow through this valve, valve 448 and conduit 82 to the lower portion of the cylinder 80. The piston 64 will now be moved upwardly to an extent determined by a stop abutment 452 associated with the cylinder, see FIG. 3, thereby causing the table 54 to swing in a counterclockwise direction, so that the toe band 22 will wipe the upper materials heightwise around the toe end of the last, this swinging movement of the table being arrested just as the wipers 20, 20 reach the plane of the insole with the upper materials clamped around the toe end of the last by the toe band 22 as shown

in FIG. 15. During this upwiping action, the retarder engages the upper materials so that a pull is exerted on the upper materials tending to stretch them about the last.

5 The conduit 186 which leads to the cylinder 184 through a flow control valve 545 and a check valve 456 is connected to the main supply line 400 through another so-called direction valve 460, a pilot-operated dump valve 462 and the valve 408, mentioned above. A mechanically operated valve 466 is interposed in a conduit 464 which leads from the pilot-operated dump valve 462 to the main supply line 400, and this mechanically operated valve is arranged to be actuated by the table 54 at the end of its upward movement, as diagrammatically illustrated in FIG. 18. When this occurs, the dump valve 462 will be actuated to disconnect the conduit 186 from the valve 408 and to connect this conduit, and thus the cylinder 184 to exhaust through the direction valve 460 and dump valve 462. The spring 188, FIG. 3, will now 10 swing the supporting arm 160 in a counterclockwise direction, FIG. 4, and elevate the retarder 24 and insole holdown 26 to the retracted positions in which these 15 parts are shown in dotted lines in FIG. 15.

The operator is thus afforded an opportunity, while 20 the upper materials are held by the toe band, to perform whatever operations on the upper materials or shoe as may be appropriate, such, for example, as trimming out the innermost layers of the upper materials around the toe end of the shoe and/or applying a suitable adhesive 25 around the toe end of the insole. Also, he may use hand pincers to impart additional tensioning or positioning pulls on the upper materials. Having done these things, he will now move the valve 406, which is similar to valve 404, by the depression of a hand lever 470, FIG. 30 2, from the intermediate position in which it is shown in FIG. 18, to its operative position in which a conduit 472 is connected to the main supply line 400. Fluid under pressure from the conduit 472 will now actuate the direction valve 460 to connect the conduit 186 to 35 the conduit 472, thus causing the retarder and insole holdown to be returned to their full-line operative positions shown in FIG. 15. The conduit 472 is also connected, through a sequence valve 476 with the conduit 61 which leads to the wiper operating cylinder 58. Thus, as 40 pressure builds up in the conduit 472, after the retarder and insole holdown have been returned to their operative positions, the sequence valve 476 will open and the wipers 20, 20 will be advanced and closed by the piston 60, see FIG. 16, which shows the wipers at the 45 conclusion of their advancing and closing movements.

Referring to FIG. 2, there is attached to a portion of the wiper operating rod 52, a wedge-shaped cam block 480 which is adapted to actuate the plunger 482 of a combined control and pressure regulator valve 484. This combined valve arrangement, which is of conventional construction and diagrammatically illustrated in FIG. 18, is so arranged that when the plunger 482 is in its outermost position, see FIG. 2, the conduit 84 is connected to exhaust through a pilot valve 486, forming a part of the combined control and pressure regulator valve. Now, as the plunger is moved to the left, FIG. 2, or upwardly in FIG. 18, by the cam 480 as the wiper operating rod moves downwardly in FIG. 2 and to the left in FIG. 18, the conduit 84 will first be connected to the conduit 416, through a pressure regulator valve 488, also forming part of the combined control and pressure regulator valve 484, and then, as movement of the plunger 482 continues, the pressure of the fluid admitted to the conduit 84 and thence to the upper part of the cylinder 80 will be increased. Thus, as the wipers are advanced and closed 60 to wipe the lasting margin of the upper materials inwardly over the bottom of the insole at the toe end of the shoe, the pressure of the wipers exerted on the upper materials will be progressively increased. In this connection, it 65 may be explained that the pressure of the fluid admitted

beneath the piston 64 through the conduit 82 is considerably less than that of the fluid which is admitted to the upper portion of the cylinder 80 through the conduit 84, this because of the setting of the pressure regulator valve 448 which controls the pressure in the conduit 82 as compared to the setting of the pressure regulator valve 488 which controls the pressure in conduit 84. Thus, there is an unbalanced force exerted on the piston rod 62 in a direction to swing the table 54 downwardly, FIGS. 3 and 17. Initially, as the wipers commence their overwiping action, this unbalanced force is relatively small so that a light wiping pressure is yieldingly applied through the action of spring 78. However, as the wipers continue to advance and close this unbalanced force increases as does the pressure applied on the upper materials by the wipers. As will be apparent, by providing a suitably shaped cam 480, the force exerted by the wipers during their advancing and closing movements may be varied as desired to suit different operating conditions.

After the advanced and closed wipers have applied pressure to the wiped-in lasting margin of the upper materials, i.e., have applied bedding pressure, for a desired interval of time, the operator will again actuate the knee lever 410 to return the valve 402 to the position in which it is shown in FIG. 18, thereby connecting the conduits 354 and 412 to the main supply line 400 and connecting conduits 414, 416 and 418 to exhaust. Cylinder 290 and one end of the cylinder 348 will now be connected to exhaust through conduit 414, while fluid under pressure will be admitted to the opposite end of the cylinder 348 through the conduit 354, thereby lowering the toe pad 32 and withdrawing the heel band 34 from shoe clamping position. As conduit 416 is connected to exhaust, conduit 84, which leads to the upper end of the cylinder 80, is also connected to exhaust through the valve 486 so that bedding pressure is relieved.

As conduit 418 is connected to exhaust through valve 402, two check valves 490 and 492 are released, thus exhausting conduits 436 and 438. Cylinders 116, 124, 172 and 174 are connected to exhaust through conduit 436 so that the toe band 22 is retracted to its inoperative position while the retarder 24 and insole holdown 26 are elevated to the positions shown in FIG. 4. Upon the exhausting of conduit 438, valve 460 will be returned to the position shown in FIG. 18 so that cylinders 58 and 184 are connected to exhaust. Thus the wipers will be retracted and opened and the supporting arm 160 will be moved to its inoperative position by spring 188.

As shown in FIG. 18, the conduit 412 leads to the directional valve 446 through a mechanically operated valve 496, and the latter valve is provided with an operating plunger 498, see FIG. 2. Carried by the wiper operating rod 52 is a cam 500 which is adapted to engage the plunger 498 as the wipers are advanced and closed, thereby moving this valve from the position shown in FIG. 18, in which that part of the conduit 412 which is connected to the valve 446 is connected to exhaust, to a position in which the two parts of the conduit 412 are connected together through the valve 496. Thus, when conduit 82 is connected to exhaust through the conduit 436 and the valve 404, fluid under pressure will be supplied to the lower part of the cylinder 80 through the valve 496, conduit 412 and direction valve 446 so that the wipers 20, 20 may be retracted, as conduit 61 is connected to exhaust through valve 476 and conduit 472, with the wiper head held elevated and without danger of the wipers disturbing the upper material on the bottom of the shoe. When the wipers are thus retracted, the cam 500 will leave the plunger 498 so that valve 496 is returned to its original position to connect the conduit 412 to exhaust and the conduit 82 to exhaust through valve 496. The table 54 on which the wipers are mounted will now swing downwardly under

the action of gravity and valve 466 will return to its original position to connect conduit 186 to the supply line 400 thus causing the supporting arm 160 to be returned to its operative position as shown in FIG. 4.

5 Valve 408 is mounted on the front of the machine frame, FIGS. 1 and 2, and has an operating handle 510 by means of which it may be moved from the position shown in FIG. 18, in which conduit 186 is connected to the main supply line 400, to another position in which the conduit 186 is connected to exhaust. By so moving this valve, the operator may cause the retarder 24 and insole holdown 26 to be elevated to the dotted line inoperative position shown in FIG. 15 at any time before, during, or after each operation of the machine.

10 15 Conduit 472 opens into conduits 436 and 438 through the check valve 492. Thus, if the operator, after operating valve 402 to jack the shoe, in the manner explained above, then immediately moves the valve 406 to its operative position, to connect conduit 472 to the main supply line 400, conduits 436 and 438 will also be connected to the main supply line 400 and the machine will go through a complete operating cycle without interruption. Such fully automatic operating cycle can be used when lasting pretrimmed and pre cemented shoes.

20 25 Although the operation of the machine has, in a general way, been suggested in the foregoing detailed description of its construction, it will now be briefly reviewed. When the shoe S to be lasted is presented to the machine, the supporting arm 160 will be in its operative position and the retarder 24 and holdown 26 will be in their inoperative positions as shown in FIG. 4 of the drawings. Accordingly, the operator, in presenting a shoe to the machine, will bring its toe end into engagement with the retarder and, after swinging the shoe

25 30 laterally about its toe end as a pivot to align its forepart with the longitudinal center line of the wipers 20, 20, he will strike the knee pad 410, thus causing the shoe to be clamped against the shoe rest 30 by the toe pad 32, FIG. 12, and to be engaged by the heel band 34, FIG. 3.

35 40 If the operator is not entirely satisfied with the exact position of the shoe in the machine, he may, by a second actuation of the knee pad, release it for repositioning and reclamping. Otherwise, he will depress the hand lever 434 to initiate the upwiping and upper tensioning actions, whereupon the retarder 24, holdown 26, and toe band 22 will immediately assume the positions shown in FIG. 14 of the drawings. As will be apparent from this figure, the toe band will be advanced to a position for engaging the upper materials to shape

45 50 them to the last, and the lasting margin of the upper U will now be clamped, yieldingly, against the top of the toe band as the wiper head 50 is now elevated. Because of the action of the retarder, a pull will be exerted on the upper materials in a heightwise direction tending to

55 60 stretch the upper materials about the last as the upper materials are drawn out from between the top of the toe band and lower edge of the retarder. At the conclusion of the upward movement of the wiper head, the toe band, retarder and insole holdown will assume the positions shown in solid lines in FIG. 15 and immediately thereafter, the supporting arm 160 will be moved to its inoperative position, by the action of the spring 188 when cylinder 184 is connected to exhaust, thus retracting the retarder and holdown to the dotted-line positions shown in FIG. 15.

65 70 During its upper shaping action, which occurred as the wiper head 50 was being elevated, the toe band yieldingly pressed the upper materials against the last as the result of the action of piston 116 and piston 126 and cylinder 124, and this band now holds the upper materials against loosening or retracting. With the entire toe end of the shoe and also the lasting margin of the upper materials thus exposed, the operator is afforded an opportunity to trim out the box toe and lining and/or to hand

75 75 pincer the upper materials as he desires. In addition,

he may apply a band or ribbon of thermoplastic adhesive around the marginal edge of the toe end of the insole, for example, by means of a hand gun of the type schematically shown in FIG. 1 and designated by the reference character H, immediately before initiating the overwiping and bedding down action of the wipers by the depression of the hand lever 470. During the advancing and closing of the wipers which now occurs, the retarder 24 is operative to control the lasting margin and may be wedged upwardly as the lasting margin is wiped inwardly and drawn from beneath the retarder and the holdown 26 will eventually be swung about its pivot pin 217 against the resistance of the spring 218, by the fully advanced wipers, the parts finally coming to rest in the positions shown in FIG. 16 and with the wipers exerting a bedding down pressure on the overwiped lasting margin. As will be recalled, this downward pressure of the wipers on the upper material was progressively increased as the wipers advanced as the result of the action of the cam 480 on the pressure regulator valve 488. Hence, when the wiping action has been completed, the wipers will be exerting a substantial pressure on the upper materials. After permitting the wipers to remain in this bedding down position for any desired interval, the operator, while grasping the shoe with one hand, will strike the knee pad, thus releasing the shoe and causing the various operating elements of the machine to be returned to their original positions as shown in FIG. 4.

Having thus described my invention, what I claim is new and desire to secure by Letters Patent of the United States is:

1. A machine for lasting the toe ends of shoes having, in combination, a support for a shoe comprising upper materials and an insole assembled on a last, means for shaping the upper materials of a shoe on the support around the toe end of its last in response to relative heightwise movement between said upper shaping means and the shoe support, means for effecting said relative heightwise movement, a member adapted to engage the upper materials and to cooperate with the upper shaping means during such relative heightwise movement to cause a pull to be exerted on the upper materials tending to stretch them about the last, means for supporting said member mounted for movement from an operative position to an inoperative position, means for moving said supporting member to and holding it in operative position during said relative heightwise movement between the upper shaping means and the shoe support, and means for moving the supporting means to its inoperative position thereby to retract said member from the upper materials and the toe end of the shoe at the conclusion of such relative heightwise movement.

2. A machine for lasting the toe ends of shoes having, in combination, a support for a shoe comprising upper materials and an insole assembled on a last, a toe band for shaping the upper materials of a shoe on the support around the toe end of its last in response to relative heightwise movement between said toe band and the shoe support, fluid pressure operated means for effecting said relative heightwise movement, a member adapted to engage the upper materials and to cooperate with the toe band during such relative heightwise movement to cause a pull to be exerted on the upper materials tending to stretch them about the last, means supporting said member mounted for movement from an operative position to an inoperative position, fluid pressure operated means for moving said supporting member to and holding it in operative position during said relative heightwise movement between the toe band and the shoe support, spring means for moving the supporting means to its inoperative position, and means for connecting said last-named fluid pressure operated means to exhaust to cause said spring means to move the supporting means to inoperative position and thereby to retract said member from the upper

materials and the toe end of the shoe at the conclusion of such relative heightwise movement.

3. A machine for lasting the toe ends of shoes having a support for a shoe comprising upper materials and an insole assembled on a last, means for shaping the upper materials of a shoe on the support about the toe end of its last in response to relative heightwise movement between said lasting means and the shoe support, means for effecting said relative heightwise movement, a member adapted to engage the upper materials and to cooperate with the upper shaping means during such relative heightwise movement to cause a pull to be exerted on the upper materials tending to stretch them over the last, a member adapted to engage the insole adjacent to the toe end of the last during such relative heightwise movement between the upper shaping means and the support, means supporting said members mounted for movement from an operative position to an inoperative position, means for moving said supporting means to and holding it in operative position during relative heightwise movement between the lasting means and the shoe support, and means for moving the supporting means to its inoperative position thereby to retract said members from engagement with the upper materials and the insole at the conclusion of such relative heightwise movement.

4. A machine for lasting the toe ends of shoes having a support for a shoe comprising upper materials and an insole assembled on a last, a toe band for shaping the upper materials of a shoe on the support about the toe end of its last in response to relative heightwise movement between said toe band and the shoe support, fluid pressure operated means for effecting said relative heightwise movement, a member adapted to engage the upper materials and to cooperate with the toe band during such relative heightwise movement to cause a pull to be exerted on the upper materials tending to stretch them over the last, a member adapted to engage the insole adjacent to the toe end of the last during such relative heightwise movement between the toe band and the support, means supporting said members mounted for movement from an operative position to an inoperative position, fluid pressure operated means for moving said supporting means to and holding it in operative position during relative heightwise movement between the toe band and the shoe support, spring means for moving the supporting means to its inoperative position, and means for connecting said last-named fluid pressure operated means to exhaust to cause said spring means to move the supporting means to inoperative position thereby to retract said members from engagement with the upper materials and the insole at the conclusion of such relative heightwise movement.

5. A machine for lasting the toe ends of shoes having, in combination, a support for a shoe comprising upper materials and an insole assembled on a last, means for shaping the upper materials of a shoe on the support around the toe end of its last in response to relative heightwise movement between the upper shaping means and the shoe support, means for effecting said relative heightwise movement, a first manually operable control means for initiating action of said heightwise movement effecting means, a member adapted to engage the upper materials during such relative heightwise movement to cause a pull to be exerted on the upper materials tending to stretch them about the last, means supporting said member mounted for movement from an operative position to an inoperative position, means for moving said supporting member to and holding it in operative position during said relative heightwise movement, means for moving the supporting means to its inoperative position thereby to retract said member from the upper materials and the toe end of the shoe at the conclusion of such relative heightwise movement, toe wipers for wiping the lasting margin of the upper materials inwardly over the toe end of the insole, means for operating said wipers, and a second manually operable control means for ini-

tiating action of the wiper operating means, said last-named control means also being adapted to effect return of said supporting means to operative position so that said member is effective to control the lasting margin of the upper materials as it is wiped inwardly over the insole by said wipers.

6. A machine for lasting the toe ends of shoes having, in combination, a support for a shoe comprising upper materials and an insole assembled on a last, a toe band for shaping the upper materials of a shoe on the support around the toe end of its last in response to relative heightwise movement between said toe band and the shoe support, fluid pressure operated means for effecting said relative heightwise movement, a first manually operable control means for initiating action of said heightwise movement effecting means, a member adapted to engage the upper materials during such relative heightwise movement to cause a pull to be exerted on the upper materials tending to stretch them about the last, means supporting said member mounted for movement from an operative position to an inoperative position, fluid pressure operated means for moving said supporting member to and holding it in operative position during said relative heightwise movement, spring means for moving the supporting means to its inoperative position, means for connecting said last-named fluid pressure operated means to exhaust to cause said spring means to move the supporting means to inoperative position thereby to retract said member from the upper materials and the toe end of the shoe at the conclusion of such relative heightwise movement, toe wipers for wiping the lasting margin of the upper materials inwardly over the toe end of the insole, fluid pressure means for operating said wipers, and a second manually operable control means for initiating action of the wiper operating means, said last-named control means also being adapted to render the fluid pressure operated means associated with the supporting means operable to return said supporting means to operative position so that said member is effective to control the lasting margin as it is wiped inwardly over the insole by the wipers.

7. A machine for lasting the toe ends of shoes having a support for a shoe comprising upper materials and an insole assembled on a last, means for shaping the upper materials of a shoe on the support about the toe end of its last in response to relative heightwise movement between said upper shaping means and the shoe support, means for effecting said relative heightwise movement, a first manually operable control means for initiating action of said heightwise movement effecting means, a member adapted to engage the upper materials during such relative heightwise movement to cause a pull to be exerted on the upper materials tending to stretch them over the last, a member adapted to engage the insole adjacent to the toe end of the last during such relative heightwise movement, means for supporting said members mounted for movement from an operative position to an inoperative position, means for moving said supporting means to and holding it in operative position during said relative heightwise movement, and means for moving the supporting means to its inoperative position thereby to retract said members from engagement with the upper materials and the insole at the conclusion of such relative heightwise movement, toe wipers for wiping the lasting margin of the upper materials inwardly over the toe end of the insole, means for operating said wipers, and a second manually operable control means for initiating action of the wiper operating means, said last-named control means also being adapted to effect return of said supporting means to operative position so that said first-mentioned member is effective to control the lasting margin as it is wiped inwardly over the insole by the wipers.

8. A machine for lasting the toe ends of shoes having a support for a shoe comprising upper materials and an insole assembled on a last, a toe band for shaping the upper materials of a shoe on the support about the toe

end of its last in response to relative heightwise movement between said toe band and the shoe support, fluid pressure operated means for effecting said relative heightwise movement, a first manually operable control means for initiating action of said heightwise movement effecting means, a member adapted to engage the upper materials during such relative heightwise movement to cause a pull to be exerted on the upper materials tending to stretch them over the last, a second member adapted to engage the insole adjacent to the toe end of the last during such relative heightwise movement, means for supporting said members mounted for movement from an inoperative position to an operative position, fluid pressure operated means for moving said supporting means to and holding it in operative position during said relative heightwise movement, spring means for moving the supporting means to its inoperative position, means for connecting said fluid pressure operated means to exhaust to cause said spring means to move the supporting means to inoperative position thereby to retract said members from engagement with the upper materials and the insole at the conclusion of such relative heightwise movement, toe wipers for wiping the lasting margin of the upper materials inwardly over the toe end of the insole, fluid pressure operated means for operating said wipers, and a second manually operable control means for initiating action of the wiper operating means, said last-named control means also being adapted to render the fluid pressure operated means associated with the supporting means operable to return said supporting means to operative position so that said first-mentioned member is effective to control the lasting margin as it is wiped inwardly over the insole by the wipers.

9. A machine for lasting the toe ends of shoes having a support for a shoe comprising upper materials and an insole assembled on a last, means for shaping the upper materials of a shoe on the support in response to relative heightwise movement between said upper shaping means and the shoe support, means for effecting said relative heightwise movement, a retarder adapted to engage the upper materials and to cooperate with the upper shaping means during such relative heightwise movement to cause a pull to be exerted on the upper materials tending to stretch them over the last, means for supporting said retarder mounted for movement from an operative position to an inoperative position, means for moving said supporting means to and for holding it in operative position during said relative heightwise movement, and means for moving the supporting member to its inoperative position thereby to retract said retarder from the upper materials at the conclusion of such relative heightwise movement.

10. A machine for lasting the toe ends of shoes having a support for a shoe comprising upper materials and an insole assembled on a last, a toe band for shaping the upper materials of a shoe on the support about the toe end of its last in response to relative heightwise movement between said toe band and the shoe support, fluid pressure operated means for effecting said relative heightwise movement, a retarder adapted to engage the upper materials and to cooperate with the toe band during such relative heightwise movement to cause a pull to be exerted on the upper materials tending to stretch them about the last, means supporting said retarder mounted for movement from an operative position to an inoperative position, fluid pressure operated means for moving said supporting means to and for holding it in operative position during said relative heightwise movement, spring means for moving the supporting means to its inoperative position, and means for connecting said last-mentioned fluid pressure operated means to exhaust to cause said spring means to move the supporting means to inoperative position thereby to retract said retarder from the upper materials at the conclusion of such relative heightwise movement.

11. A machine for lasting the toe ends of shoes hav-

ing a support for a shoe comprising upper materials and an insole assembled on a last, means for shaping the upper materials of a shoe on the support about the toe end of its last in response to relative heightwise movement between said lasting means and the shoe support, means for effecting said relative heightwise movement, a retarder adapted to engage the upper materials and to cooperate with the upper shaping means during such relative heightwise movement to cause a pull to be exerted on the upper materials tending to stretch them over the last, a holddown for engaging the toe end of the insole during such relative heightwise movement, means supporting said retarder and holddown mounted for movement from an operative position to an inoperative position, means for moving said supporting means to and for holding it in operative position during said relative heightwise movement, and means for moving the supporting means to its inoperative position thereby to retract said retarder and holddown from the upper materials and the insole at the conclusion of said relative heightwise movement.

12. A machine for lasting the toe ends of shoes having a support for a shoe comprising upper materials and an insole assembled on a last, a toe band for shaping the upper materials of a shoe on the support about the toe end of its last in response to relative heightwise movement between said toe band and the shoe support, fluid pressure operated means for effecting said relative heightwise movement, a retarder adapted to engage the upper materials and to cooperate with the toe band during such relative heightwise movement to cause a pull to be exerted on the upper materials tending to stretch them about the last, a holddown for engaging the toe end of the insole during such relative heightwise movement, means supporting said retarder and holddown mounted for movement from an operative position to an inoperative position, fluid pressure operated means for moving said supporting means to and for holding it in operative position during said relative heightwise movement, spring means for moving the supporting means to its inoperative position, and means for connecting said last-mentioned fluid pressure operated means to exhaust to cause said spring means to move the supporting means to inoperative position thereby to retract said retarder and holddown from the upper materials and insole at the conclusion of said relative heightwise movement.

13. A machine for lasting the toe ends of shoes having a support for a shoe comprising upper materials and an insole assembled on a last, means for shaping the upper materials of a shoe on the support about the toe end of its last in response to relative heightwise movement between said upper shaping means and the shoe support, means for effecting said relative heightwise movement, a first manually operable control means for initiating action of said heightwise movement effecting means, a retarder adapted to engage the upper materials during such relative heightwise movement to cause a pull to be exerted on the upper materials tending to stretch them about the last, means supporting said retarder mounted for movement from an operative position to an inoperative position, means for moving said supporting means to and for holding it in operative position during said relative heightwise movement, means for moving the supporting means to its inoperative position thereby to retract said retarder from the upper materials at the conclusion of such relative heightwise movement, toe wipers for wiping the lasting margin of the upper materials inwardly over the toe end of the insole, means for operating said wipers, and a second manually operable control means for initiating action of the wiper operating means, said last-named control means also being adapted to effect return of said supporting means to operative position so that said retarder is effective to control the lasting margin as it is wiped inwardly over the insole by the wipers.

14. A machine for lasting the toe ends of shoes having a support for a shoe comprising upper materials and an

insole assembled on a last, a toe band for shaping the upper materials of a shoe on the support about the toe end of its last in response to relative heightwise movement between said toe band and the shoe support, fluid pressure operated means for effecting said relative heightwise movement, a first manually operable control means for initiating action of said heightwise movement effecting means, a retarder adapted to engage the upper materials during said relative heightwise movement to cause a pull to be exerted on the upper materials tending to stretch them about the last, means supporting said retarder mounted for movement from an operative position to an inoperative position, fluid pressure operated means for moving said supporting means to and for holding it in operative position during said relative heightwise movement, spring means for moving the supporting means to its inoperative position, mean for connecting said last-mentioned fluid pressure operated means to exhaust to cause said spring means to move the supporting means to inoperative position thereby to retract said retarder from the upper materials at the conclusion of such relative heightwise movement, toe wipers for wiping the lasting margin of the upper materials inwardly over the toe end of the insole, fluid pressure means for operating said wipers, and a second manually operable control means for initiating action of the wiper operating means, said last-named control means also being adapted to render the fluid pressure operated means associated with the supporting means operative to return said supporting means to operative position so that said retarder is effective to control the lasting margin as it is wiped inwardly over the insole by the wipers.

15. A machine for lasting the toe ends of shoes having a support for a shoe comprising upper materials and an insole assembled on a last, means for shaping the upper materials of a shoe on the support about the toe end of its last in response to relative heightwise movement between said upper shaping means and the shoe support, means for effecting said relative heightwise movement, a first manually operable control means for initiating action of said heightwise movement effecting means, a retarder adapted to engage the upper materials during such relative heightwise movement to cause a pull to be exerted on the upper materials tending to stretch them about the last, a holddown for engaging the toe end of the insole during such relative heightwise movement, means supporting said retarder and holddown mounted for movement from an operative position to an inoperative position, means for moving said supporting means to and for holding it in operative position during said relative heightwise movement and means for moving the supporting means to its inoperative position thereby to retract said retarder and holddown from the upper materials and insole at the conclusion of such relative heightwise movement, toe wipers for wiping the lasting margin of the upper materials inwardly over the toe end of the insole, means for operating said wipers, and a second manually operable control means for initiating action of the wiper operating means, said last-named control means also being adapted to effect return of said supporting means to operative position so that said retarder is effective to control the lasting margin as it is wiped inwardly over the insole by the wipers.

16. A machine for lasting the toe ends of shoes having a support for a shoe comprising upper materials and an insole assembled on a last, a toe band for shaping the upper materials of a shoe on the support about the toe end of its last in response to relative heightwise movement between the toe band and the shoe support, fluid pressure operated means for effecting said relative heightwise movement, a first manually operable control means for initiating action of said heightwise movement effecting means, a retarder adapted to engage the upper materials during such relative heightwise movement to cause a pull to be exerted on the upper materials tending to stretch

them about the last, a holddown for engaging the toe end of the insole during such relative heightwise movement, means for supporting said retarder and holddown mounted for movement from an operative position to an inoperative position, fluid pressure operated means for moving said supporting means to and for holding it in operative position during said relative heightwise movement, spring means for moving the supporting means to its inoperative position, means for connecting said last-mentioned fluid pressure operated means to exhaust to cause said spring means to move the supporting means to inoperative position thereby to retract said retarder and holddown from the upper materials and insole at the conclusion of such relative heightwise movement, toe wipers for wiping the lasting margin of the upper materials inwardly over the toe end of the insole, fluid pressure means for operating said wipers, and a second manually operable control means for initiating action of the wiper operating means, said last-named control means being adapted to render the fluid pressure operated means associated with the supporting means operable to return said supporting means to operative position so that said retarder is effective to control the lasting margin as it is wiped inwardly over the insole by the wipers.

17. A machine for lasting the end portion of a shoe having a support for a shoe comprising upper materials and an insole assembled on a last, end embracing wipers mounted in a wiper head for advancing and closing movements to wipe the lasting margin of the upper materials of a shoe on the support inwardly over the insole at an end portion of the shoe, means for effecting such advancing and closing movements of said wipers, said wiper head and said shoe support being mounted for relative movement in a direction extending heightwise of a shoe on the support to cause the wipers to press the lasting margin of the upper materials against the insole as the wipers are advanced and closed, fluid pressure operated means for effecting such relative movement in the mentioned direction, and means operable in response to the advancing and closing movements of the wipers for controlling the pressure of operating fluid supplied to said fluid pressure operated means, thereby to vary the force exerted on the lasting margin by the wipers as the wipers are advanced and closed.

18. A machine for lasting the end portion of a shoe having a support for a shoe comprising upper materials and an insole assembled on a last, end embracing wipers mounted in a wiper head for advancing and closing movements to wipe the lasting margin of the upper materials of a shoe on the support inwardly over the insole at an end portion of the shoe, means for effecting such advancing and closing movements of said wipers, said wiper head and said shoe support being mounted for relative movement in a direction extending heightwise of a shoe on the support to cause the wipers to press the lasting margin of the upper materials against the insole as the

wipers are advanced and closed, fluid pressure operated means for effecting such relative movement in the mentioned direction, and a cam movable in response to the advancing and closing movements of the wipers for controlling the pressure of the operating fluid supplied to said fluid pressure operating means, thereby to vary the force exerted on the lasting margin by the wipers, as the wipers are advanced and closed.

19. A machine for lasting the end portion of a shoe having a support for a shoe comprising upper materials and an insole assembled on a last, end embracing wipers mounted in a wiper head for advancing and closing movements to wipe the lasting margin of the upper materials of a shoe on the support inwardly over the insole at an end portion of the shoe, means for effecting such advancing and closing movements of said wipers, said wiper head and said shoe support being mounted for relative movement in a direction extending heightwise of a shoe on the support to cause the wipers to press the lasting margin of the upper materials against the insole as the wipers are advanced and closed, fluid pressure operated means for effecting such relative movement in the mentioned direction, a pressure regulator valve having a displaceable member for controlling the pressure of the operating fluid supplied to said fluid pressure operated means, means operable in response to the advancing and closing movements of the wipers for displacing said displaceable member thereby to vary the force exerted on the lasting margin by the wipers as the wipers are advanced and closed.

20. A machine for lasting the end portion of a shoe having a support for a shoe comprising upper materials and an insole assembled on a last, end embracing wipers mounted in a wiper head for advancing and closing movements to wipe the lasting margin of the upper materials of a shoe on the support inwardly over the insole at an end portion of the shoe, means for effecting such advancing and closing movements of said wipers, said wiper head and said shoe support being mounted for relative movement in a direction extending heightwise of a shoe on the support to cause the wipers to press the lasting margin of the upper materials against the insole as the wipers are advanced and closed, fluid pressure operated means for effecting such relative movement in the mentioned direction, a pressure regulator valve having a displaceable member for controlling the pressure of the operating fluid supplied to said fluid pressure operated means, and a cam movable in response to the advancing and closing movements of the wipers for displacing said displaceable member thereby to vary the force exerted on the lasting margin by the wipers as the wipers are advanced and closed.
